UNITED STATES PATENT OFFICE.

WATSON CUTHERBERT, OF CLEVELAND, OHIO, ASSIGNOR, BY MESNE ASSIGNMENTS, TO THE RE FIL BROOM COMPANY, OF CLEVELAND, OHIO, A CORPORATION OF OHIO.

BROOM.

Application filed December 31, 1921. Serial No. 536,243.

To all whom it may concern:

Be it known that I, WATSON CUTHERBERT, a citizen of the United States, post-office address 2088 Murray Hill Road, in the city of Cleveland, in the county of Cuyahoga and State of Ohio, have invented certain new and useful Improvements in Brooms, of which the following is a specification.

My invention relates to improvements in 10 brooms and the like and the object of the invention is to devise a broom in which the straw portion and handle are replaceable, independently, and which will be cheap and simple to manufacture.

15 Another object of the invention is to devise a more simple and economical method of construction whereby the broom shall be simple in construction and convenient and reliable in use, holding the filling more firmly than heretofore and at the same time 20 being more easily refilled.

Another object is the overcoming of defects of the construction set forth in my former patent for brooms No. 1,410,284.

25 My invention consists of a holder portion having a threaded orifice in its upper end, a spring wedge member within the holder, a straw portion adapted to be inserted into the lower part of the holder below the wedge, 30 a conical portion located in between the sides of the wedge and attached to the handle portion for spreading the wedge, a handle threaded at its lower end and engaging the threaded orifice in the holder, the lower end 35 of the handle coacting with the conical portion first and later with the spring wedge to force it into the upper part of the straw portion and against the sides of the holder for securing the straw firmly in place in the 40 holder all as more particularly described and illustrated in the accompanying drawings in which:

Figure 1 is a side sectional elevation of my broom constructed according to my invention, the parts being in position for forcing the spring wedge into the straw portion of the broom.

Figure 2 is a sectional elevation on the line 2—2 of Figure 1.

50 Figure 3 is a sectional view of a broken section of the form in which the straw portion is made up and packed before being inserted in the holder.

Figure 4 is a section on the line 4—4 of 55 Figure 3.

Figures 5 and 6 are similar views to Figures 1 and 2 respectively, the parts being in their normal positions.

Like characters of reference indicate corresponding parts in the different views. 60

1 is the holder portion having the threaded orifice 2. 3 is a ribbed or beaded portion in proximity to the lower edge of the holder 1. 4 is the concave portion on the inner two sides of the holder 1. 5 is the spring wedge 65 for holding the straw portion firmly in said holder. 6 is the conical portion coacting immediately with the spring wedge and is fastened to the handle by suitable means. 7 is a pin for holding the conical portion 6 and 70 the ferrule 8 firmly together and to the handle. Intermediate of the ends of the conical portion 6 the conical portion is so formed as to make a ledge 9, upon which the top edge of the spring wedge hangs when loose by 75 means of the bent portion 10.

Now it will be seen that when the straw portion has been inserted into the holder and the handle advanced by screwing in, the conical portion exerts a slightly spreading action upon the spring wedge which is also forced slightly forward to sufficiently hold the straw portion from slipping out of its proper position. As the handle is being screwed further to its limit, the spring wedge 80 is forced into the straw portion, as shown in Figures 5 and 6, the upper neck portion thereof is snugly set in the ferrule 8, and the lower portion of the same being below the lower end of the holder 1, thereby takes all 85 of the sweeping strain off the straw portion. By thus relieving the strain from the straw portion it is necessary to have only one row of stitching around the straw instead of 90 three or four or more as heretofore to give 95 stability.

In the ordinary type of broom, much longer and more expensive straw must be used than is the case with a broom made according to my invention for which short and cheap straw is quite suitable. A further advantage of my broom lies in the cheapness of manufacture as there is no expert workmanship required.

The greatest advantage of my broom is of course the feature whereby the straw portion can be renewed independently of the other parts so that the broom will last a life time and when the straw is worn out only a very small outlay is involved in making the 105 110

broom as good as new. The handle, if it becomes broken, is also replaceable independently of any other part.

From the foregoing it will be seen that I have devised a broom which will enable a very great saving to be effected by practically the whole community.

While the specifications refer to brooms, many modifications may be made without departing from the spirit of the same or the scope of the claims and the form shown is to be taken as illustrative and not in a limiting sense. For instance it may be adapted to whisk brooms or brushes of various kinds.

What I claim as my invention is:

1. In a broom, the combination of a straw portion, a holder for the straw portion, a spring wedge, the spring wedge consisting of plates fixed together at one edge and means for spreading the plate of the spring wedge to cause it to secure the straw portion in said holder, substantially as described.

2. In a broom, the combination of a straw portion, a holder for the straw portion, a spring wedge, and means for spreading and advancing the spring wedge to cause it to be forced into the straw portion to secure same in said holder, substantially as described.

3. In a broom, the combination of a straw portion, a holder for the straw portion, a spring wedge, the spring wedge consisting of plates fixed together at their lower edges, a handle threaded in the holder, and the handle having a conical end for spreading the plates of the spring wedge to cause it to secure the straw portion in said holder, substantially as described.

4. In a broom, the combination of a straw portion, a hollow holder for the straw portion, a spring wedge in said holder, a han-

dle threaded in the holder, the handle having a conical end for spreading the spring wedge to cause it to secure the straw portion in said holder, and means loosely connecting the spring wedge to the handle, substantially as described.

5. In a broom, the combination of a straw portion, a hollow holder for the straw portion, a spring wedge in said holder, a handle threaded in the holder, the handle having a conical end for spreading the spring wedge to cause it to secure the straw portion in said holder, the handle having a ledge, and the spring wedge having a bent portion for engaging the ledge to loosely connect the spring wedge to the handle, substantially as described.

6. In a broom, the combination of a straw portion, a hollow holder for the straw portion, a spring wedge in said holder, a handle threaded in the holder, the handle having a conical end for spreading the spring wedge to cause it to secure the straw portion in said holder, the spring wedge having a neck portion, and a ferrule fixed to the handle for receiving the neck portion of the spring wedge, substantially as described.

7. In a broom, the combination of a straw portion, a hollow holder for the straw portion, the holder being provided with beads at its inner sides in proximity to its lower edge, the holder having concave portions between said beads and said lower edge, a spring wedge in said holder, and means for spreading the spring wedge to cause it to force the straw portion against said beads into said concave portions of the holder for securing same in said holder, substantially as described.

In testimony whereof I affix my signature.

WATSON CUTHBERT.
